BROOM SHOULDER

Donald G. Ray, Garland, Tex., assignor to All-American Manufacturing, Inc., Winnsboro, Tex.

Continuation of design applications Ser. No. 17,959 and Ser. No. 17,984, both June 30, 1969. This application Dec. 9, 1970, Ser. No. 26,373

Term of patent 14 years

Int. Cl. D4—01
U.S. Cl. D4—4

The figure is a bottom perspective view of a broom shoulder showing my new design, the broom bristles and handle indicated by means of broken lines for illustrative purposes only and form no part of the claimed design.

This is a continuation of previously filed applications, Ser. Nos. 17,959 and 17,984, filed June 30, 1969, for Broom Shoulder.

I claim:

The ornamental design for a broom shoulder, substantially as shown and described.
